AIR COOLED SHOE

Leo W. Wroten, Anguilla, Miss.

Application November 6, 1936, Serial No. 109,571

3 Claims. (Cl. 36--3)

The present invention relates to improvements in air cooled shoes and has for an object to provide an improved shoe construction in which ventilation is furnished to the interior of the shoe.

Another object of the invention is to provide a ventilating attachment for shoes whereby the feet, particularly of walkers, will be maintained much cooler.

10 A further object of the invention aims to prevent, or reduce, perspiration of the feet, and to assist in preventing athlete's foot and other foot diseases.

15 A still further object of the invention is to provide an air cooled shoe of economical construction in which the standard construction of the shoe is not departed from and the appearance of the shoe remains substantially unchanged.

20 With the foregoing and other objects in view, the invention will be more fully described hereinafter, and will be more particularly pointed out in the claims appended hereto.

25 In the drawing, wherein like symbols refer to like or corresponding parts throughout the several views.

Figure 1 is a bottom plan view, with parts broken away and parts shown in section, of an improved air cooled shoe constructed in accordance with the present invention.

Figure 2 is a side elevation of the improved shoe with parts broken away and parts shown in section.

Figure 3 is a cross-section taken on the line 3—3 in Figure 2.

Figure 4 is a transverse section taken on the line 4—4 in Figure 1.

Figure 5 is an enlarged longitudinal section taken through the intake valve and its casing, 40 and

Figure 6 is a similar view of the outlet valve and its casing.

Referring more particularly to the drawing, 7 designates a shoe of conventional form having eyelets 8 for the shoe-laces and a sole 9.

The heel of the shoe is constructed to function as a pump and air reservoir and for this purpose such heel 10 is hollowed-out to form an interior air space 11. This air space is enclosed at its lower side by a rubber heel or lift 12 which makes an air-tight closure against the heel 10 all around the edges of the latter where the rubber fits closely thereagainst, being held in place by screws 13 or other fastenings.

55 Within the air space or reservoir 11 there is

a coil spring 14 having its ends abutting against plates 15 and 16. Advantageously this spring 14 is tapered or of frusto conical form with its uppermost convolution of greatest diameter and its lower helix of smallest diameter, with the intermediate helices of the spring gradually diminishing in diameter from the upper convolution to the lower helix. To accord with this frusto conical formation of the spring 14, the upper plate 15 will be of sufficiently large size or diameter to receive the uppermost largest convolution of the spring and to act as a wear plate to prevent this convolution, or any part of the spring 14, from coming in contact with the leather of which the heel 10 is customarily made. The plate 15 will be secured to the leather heel 10 at the upper part of the air space 11 so as not to shift around or cause any wear upon the leather or other material of the heel. The spring will naturally move on the plate 15 but such plate will absorb the friction and wear of the spring and prevent the same from being transmitted to the heel or any part of the shoe. The lower plate 16 will act in a similar manner, avoiding any wear or friction of the spring upon the rubber lift 12. This lower plate 16 may be of a smaller size or diameter. Both plates may be made of aluminum or other appropriate material. The lift 12, being of rubber, will flex into the space 11, when the weight of the wearer is placed upon the heel, causing the spring 14 to contract and placing the air in the air reservoir 11 under pressure. This action will be increased due to irregularities in the pavement.

Air is admitted into the air space 11 through a tube or pipe 17 which connects with one of the eyelets 8 of the shoe, preferably the top eyelet as shown from which clean air may be taken at a distance above the surface of the ground. The tube 17 is concealed between the lining 30 and the outer leather 31 of the shoe and passes down through the top wall of the heel 10 and is there connected with a valve casing 18 communicating with the interior air space 11 and having a valve 19 therein yieldably closed, by spring 20, against a seat formed at the inner end of a cylindrical tubular plug 21.

Air is circulated to the interior of the shoe from the space 11 by a tube or pipe 22 which connects at its rear end with the air space 11 through a valve casing 23 embedded in the front wall of the heel. This valve casing 23 contains a tubular cylindrical plug 24, the forward face of which constitutes a valve seat for a valve 25.

pressed yieldingly against such seat by a coil or other spring 26.

The tube 22 may be embedded in the sole 9 of the shoe. At its forward end it may open 5 into the shoe in any suitable manner being preferably brought to a substantially central position within the shoe at its forward terminal end and having a mouth 27 opening upwardly into the interior space of the shoe at the most confined 10 part thereof. Preferably the tube 22 is flattened or widened out at or near the mouth 27 to enlarge such mouth in order that the velocity of the air may be diminished at the point of outlet 27. This air moving at relatively great velocity, 15 due to the pumping action, through the round narrow tube 22 will enter the fan-shaped outer portion 28 of the tube which is of larger diameter and, therefore, will reduce the velocity of the air to a considerable extent before discharging 20 that air into the interior space of the shoe.

In the use of the device, the downward thrust of the coil spring 14 will cause the rubber lift 12 to bulge outwardly in the manner indicated in dotted lines in Figure 2, thus expanding the 25 area of the air reservoir or chamber 11. When the weight of the wearer of the shoe descends upon the heel, the lift 12 will be compressed back into the position shown in full lines in Figure 2, thus acting as a plunger in a pump, 30 to draw in and to expel air from, the reservoir or chamber 11. When the rubber lift 12 is thus compressed, the coil spring 14 will be contracted and the intake 19 closed against its seat in the plug 21. At the same time the pressure within 35 the reservoir 11 will exceed the load of the spring 26, requiring the opening of the outlet valve 25 and causing the confined air within the reservoir 11 to be driven forward, by this pumping action, into the tube 22 and thus to the outlet 27, where 40 such air will be liberated in a quiet manner within the interior of the shoe to ventilate the same and prevent the perspiration of the wearer's feet. When, in the act of walking, the wearer goes forward with his weight on the sole 45 9 of the shoe, lifting the heel, the coil spring 14 will expand forcing the lift 12 outwardly and tending to create a partial vacuum within the reservoir 11. This vacuum will suck the valve 25 closed, in which action it will be aided by the 50 coil spring 26. The same suction action will open the intake valve 19 against the force of its coil spring 20 and will draw air in through tube 17. On the next compressive action on the heel that air will be forced out, as hereinbefore explained, through the tube 22 and into the shoe. 55 As a person walks this performance is repeated with every step. The result is that the feet are maintained much cooler and kept substantially from perspiring to the end that a more healthful condition may be caused to prevail in the shoe.

The device will be found efficient in operation

as it is simple in construction. The parts are not exposed and the air is taken in at the top of the angle at a considerable elevation above the surface of the pavement so that dust and foreign matter will not be drawn in through the intake tube. The device does not in any sense change the nature or form of the shoe or tend in any way to foot discomfort. The appearance of the shoe remains the same as the customary form and the cost of the ventilating construction 10 is very small. The only part subject to wear is the rubber lift 12 which can be easily replaced at a cost no higher than that of replacing the heel which is now in use in all shoes.

It is obvious that various changes and modifications may be made in the details of construction and design of the above specifically described embodiment of this invention without departing from the spirit thereof, such changes and modifications being restricted only by the scope of the 20 following claims.

What is claimed is:

1. In a shoe having a heel, sole and lacing eyelets in the upper of the shoe, said heel being hollowed-out to provide an air reservoir, a resilient lift secured to the heel at its side portions and having its intermediate part adapted to move in and out of the reservoir, spring means in the reservoir for tending to move the lift outwardly thereof, an air inlet tube connecting with one 30 of the upper eyelets and extending down the side of the shoe and opening into the reservoir, an inwardly-opening check valve in said tube, a discharge tube connecting with the air reservoir and with the interior space of the shoe, and an outwardly-opening check valve in said discharge tube.

2. In a shoe having a heel and sole, said heel being hollowed-out interiorly to provide an air space having a front wall and side walls with 40 an opening at its bottom, a resilient lift placed against the lower edges of said walls and secured thereto in an air tight manner, spring means within said heel adapted to force said lift downwardly, tubular casings embedded in said front 45 wall, plugs in said casings having openings therethrough and valve seats therein, check valves movable in said casings, toward and away from said seats, spring means in the casings for urging the check valves to seated positions, tubes forming continuations of said tubular casings, one of said tubes being in communication with the outside atmosphere and forming an inlet tube, the check valve in said inlet tube opening inwardly with respect to the interior space of the 55 heel, the other tube opening into the interior of the shoe and forming a discharge tube, the check valve in said discharge tube casing opening outwardly with respect to the interior space of the heel.

LEO W. WROTON.
